UNITED STATES PATENT OFFICE

FRED A. LUNDAHL, OF MOLINE, ILLINOIS

DESIGN FOR A TOY HAND CAR

Application filed May 5, 1930. Serial No. 35,496. Term of patent 14 years.

To all whom it may concern:

Be it known that I, FRED A. LUNDAHL, a citizen of the United States, residing at Moline, in the county of Rock Island and State of Illinois, have invented a new, original, and ornamental Design for a Toy Hand Car, of which the following is a specification, reference being made to the drawing, forming a part hereof, in which the figure is a front perspective view of a toy hand car showing my new design.

I claim:

The ornamental design for a toy hand car as shown.

FRED A. LUNDAHL.
